REGISTER

Harry A. Foothrap, Harrisburg, Pa., assignor,
by mesne assignments, to Underwood Elliott
Fisher Company, New York, N. Y., a corpora-
tion of Delaware

Application November 27, 1931, Serial No. 577,617

25 Claims. (Cl. 235—144)

My invention relates to calculating mechanisms and more particularly, to improvements in column registers, so called, for writing-adding machines of the well known Elliott-Fisher type.

5 In my co-pending application, Serial No. 505,-
905, filed December 31, 1930, I have disclosed
a decimal item, or sub-total column register, for
such machines, embodying transfer restoring
mechanism adapted for automatic operation, and
10 zero-setting mechanism adapted for manual op-
eration, said mechanisms being operatively re-
lated so that the transfer restoring mechanism
will be operated as an initial function of the zero-
setting mechanism to restore any transfer ele-
15 ments which may be out of normal position, and
as a final function of the zero-setting mech-
anism, to restore any transfer elements which may
have been thrown out of normal position during
the zero-setting operation.

20 The object of my present invention, generally
stated, is to provide a column register equipped
with sets of denominational value-indicating and
number wheels respectively, arranged, as in my
co-pending application, Serial No. 532,813, filed
25 April 25, 1931, for a system of adding wherein
the limits of denominational values are different
in certain orders, for instance, as in the English
currency system, equipped with transfer, zero-
setting, and transfer restoring mechanisms, re-
30 spectively, of the type of my aforesaid applica-
tion, Serial No. 505,905, but co-operatively re-
lated to meet the different operating requirements
arising in the use of the different arrangement of
the sets of value-indicating and number wheels.

35 To the accomplishment of the stated object, and
others subordinate thereto and presently appear-
ing, a preferred embodiment of my invention has
been illustrated in the accompanying drawings,
and will now be set forth and defined in the
40 following description and claims.

In said drawings:

Figure 1 is a view in side elevation of a register constructed according to my invention, one side of the casing being removed, the parts being
45 in their normal positions.

Fig. 2 is a horizontal sectional view taken on the line 2—2 of Fig. 1.

Fig. 3 is a view of the register in front elevation, with the casing removed, and drawn to an en-
50 larged scale.

Fig. 4 is a detail view in side elevation, illus-
trating a train of value-indicating and number
wheels, respectively, for accumulating in the
register in the farthings denomination, with an
55 intermediate gear.

Fig. 5 is a similar view, looking from the oppo-
site direction, and illustrating the train of value-
indicating and number wheels, respectively, for
accumulating in said register in a pounds denomi-
nation, with an intermediate gear, 5

Fig. 6 is a detail longitudinal sectional view
taken on the line 6—6 of Fig. 2 and drawn to a
reduced scale with the parts illustrated in the po-
sition they assume in an intermediate stage of
the zero-setting operation, 10

elevation of a special transfer head forming part
of the transfer mechanism,

Fig. 20 is a perspective view of a bearing mem-
ber forming part of said special transfer head, 45

Fig. 21 is a similar view of a trip member
forming part of said special transfer head.

The invention is conveniently illustrated as ap-
plied to a combined typewriter and calculating
mechanism, of the Elliott-Fisher type, equipped 50
with one or more column registers mounted upon
a register bar. These registers, as a type, in-
clude a series of value-indicating wheels of suc-
cessively higher denominational order, and a
similar series of toothed number wheels for ro- 55

tating said indicating wheels. The number wheels are rotated by a toothed actuator laterally movable across the series of number wheels for denominational selection, as will be understood, which actuator is operated by the keys of the machine through differential mechanism, for instance as exemplified in my Patent No. 1,576,960.

Referring now to the illustrated embodiment, the base plate 1 of the register carries the usual fixed and movable clamping jaws 2 and 3 for clamping the register to the register bar 4. A locator element 5 engages notches (not shown) in said bar to accurately fix the register in position, and the usual casing 6 encloses the adding mechanism. A series of aligned value-indicating wheels of like diameter, including a farthings wheel 8 (Fig. 3), a pence wheel 9, units and tens of shillings wheels 10 and 11, respectively, and a group of pounds wheels 12, all arranged in successively higher denominational order, are journaled on a shaft 7 mounted at its opposite ends in the opposite side walls of the casing 6. Suitably delineated on the periphery of each indicating wheel, for observation through the sight opening 13, (Fig. 1), are equidistantly spaced digits 14 (Figs. 3 and 17). The farthings wheel 8 is provided with three series of such digits, each series including "1", "2" and "3" followed by "0", the pence wheel 9 bears the digits "1" to "11" followed by "00", the units of shillings wheel 10 bears the digits "1" to "9" followed by "0", while the tens of shillings wheel 11 bears five series of digits, each including "1" and "0", alternately and the pounds wheels 12 bear the usual digits "1" to "9" and "0".

The number wheels 15 (Figs. 1-4) arranged in corresponding series with the value-indicating wheels, each drive a related value-indicating wheel, in a one-to-one ratio, through a driving gear 16 fixed to the number wheel, an intermediate gear 18, and a driven gear 17 fixed to the value-indicating wheel. The usual detent and locating rollers 19 cooperate with the number wheels 15 in a manner which will be obvious.

45 The toothed master wheel 20 rotates through fixed uniform steps or increments of movement, whereas, certain of the number wheels, as the farthings and pence wheels 8 and 9 must advance by increments or steps of different lengths from those through which the shillings and pounds wheels 10, 11 and 12 advance, the former having twelve step, and the latter ten step cycles of movement. Hence, the number wheels 15 of shillings and pounds denominations are provided with ten teeth and those of the farthings and pence denomination with twelve teeth. The latter wheels are necessarily larger, since the teeth on all the number wheels are equidistantly spaced. In order that the master wheel 20 may move in a straight path across said number wheels, those of the shillings and pounds denominations are mounted for individual rotation upon one shaft 21, (Figs. 1, 4, 5 and 15), and those of the farthings and pence denominations are journaled upon a separate shaft 22, the shafts being staggered or offset in end to end relation, to align the teeth of all the number wheels at the point of meshing with said master wheel 20. The shafts 21 and 22 are suitably journaled at their outer ends in the side walls of the casing 6 and at their inner ends in a partition plate 23 located between and parallel with the side walls of the casing.

Associated with the respective denominational number wheels 15 are individual transfer de-

vices, as follows:—Peripherally spaced from said number wheels in a series of rocking transfer heads 24 one for each number wheel except that of the pounds of the highest order denomination. The heads 24 for the number wheels 15 of 5 shillings and pounds denominations on the one hand, and the head 24 for the number wheel 15 of pence denomination on the other, are freely mounted upon the shafts 25 and 26, respectively, the outer ends of which shafts are fixed in any 10 suitable manner in the opposite side walls of the casing 6 in relatively staggered or off-set relation to compensate for the staggered relation of shafts 21 and 22 and the difference in diameter between the number wheels 15, the inner ends of 15 the shafts 25 and 26 being correspondingly off-set and supported by the partition plate 23, as shown in Fig. 2. Unitary transfer and check dogs 27 and 28, respectively, (Figs. 1, 13 and 14), are pivoted on each head, as at 29, to rotate 20 the number wheel 15 of next higher order and its connected train, one step when said heads are rocked to a proper extent, and to then lock said wheels and heads against farther transferring or carrying movement. Springs 30 yieldingly main- 25 tain the dogs effective.

Associated with the transfer heads 24 are individual motor springs 31 (Fig. 1) connected to their associated heads to rock the same through individual operating mechanisms each including 30 a bell crank lever member 32 pivoted at 33 in a mounting 34, so that one end of the bell crank is normally urged in the direction of the axis of its head 24. A connecting link 35 between each associated head and operating lever, is pivoted 35 to the head, as at 36, and to the operating lever, as at 37, to assume, in the normal position of the parts, a dead center position relatively to the axis of the head, thereby providing for a toggle lock relation of the parts to maintain the motor in 40 tensioned condition.

The depending arms of the operating levers 32 intersect the links 35 at intermediate points 37 in the lengths of the links, at which points the levers and links are pivotally connected, the free ends 38, 38' of the operating levers 32 extending past the links, as shown in Fig. 1.

45 Springs 42 press the recessed arms of individual detents 41 pivoted on the mounting 34, against ends 40 journaled in the rearwardly projecting 50 ends of the links 35 to releasably maintain the links and heads 24 in dead center or straightened toggle link positions.

The respective transfer heads 24 are tripped from their normal dead center positions to enable 55 the transferring operations to take place, by the contact of a widened transfer tooth 43 on each of the corresponding number wheels 15, except that of the pence denomination, with a trip member 44 on the associated head 24 projecting into 60 the path of its transfer tooth 43. A projecting tripping lug 45 (Fig. 9), on the pence number wheel 15 is adapted to contact a laterally projecting trip member 44, (Figs. 2 and 13 to 15), on its corresponding head, because of the customary 65 wide spacing of the number wheels 15 provided at this point to facilitate reading the register. As will be understood the tripping operation is effected, in each instance, by a number wheel of 70 next lower denominational order during the step 70 of movement of the value-registering wheels 8—12 to zero registering position.

The present register is designed for adding only and therefore for one-way transfer operations. Hence, means are provided to prevent breaking 75

the straightened toggle link relation between the links 35 and their transfer heads 24 in other than the proper direction comprising a rearwardly projecting stop arm 46, (Fig. 1), on each of the operating levers 32, which stop arms overlie the rollers 40, in the normal positions of the links 35, and prevent movement of the links and related parts in the subtracting direction.

The transfer restoring mechanism includes a restoring ball 47, (Figs. 1 and 2), and ball rod 48, pivoted coaxially with the operating levers 32 and arranged to contact the free ends 38, 38' of said levers and restore the latter and associated parts to normal position after a transferring operation. Normally, the ball rod 48 lies at a point remote from the projecting ends 38, 38' of the operating levers 32, to afford the projecting ends sufficient travel in clockwise direction to enable the operating levers 32 to complete their transferring or carrying operations, the projecting ends 38, 38' at the completion of the transferring operations then lying adjacent the ball rod 48, as shown in Fig. 6.

It then becomes necessary to reset the tripped transfer or carrying mechanisms to their normal cocked positions.

The carry restoring ball 47, 48 is pressed against the projecting ends 38, 38' of the tripped operating levers 32 to return the levers to their normal positions, and straighten the toggles 24, 35, as follows: A restoring rack 49, (Figs. 1, 3 and 6), is slidably mounted for back and forth movement on the base 1 of the register, the forward end of the restoring rack normally protruding beyond the front of the register into the path of a cam (not shown) on the carriage of the machine in a manner well known in the art, to rock the restoring ball 47, 48 counter-clockwise through a toothed pinion 50 meshed with the rack and rotatable on a fixed stud 51, a toothed sector 52 meshing with the pinion and rocking upon a cross rod 53, and a bail operator 54 journaled on the cross rod 53, and operated by the sector 52 through a yielding safety connection 55. A spring 56 having its opposite ends connected to a fixed stud 57 and to the sector 52, respectively, returns the transfer restoring mechanism to normal position, a lug 58 on the sector 52 picking up the bail operator 54 as will be clear.

Coming now to the zero-setting mechanism, in my co-pending application, Serial No. 505,905, before mentioned, the number wheels are set to zero by a simple efficient mechanism for rotating the number wheel shaft a complete cycle of movement and for picking up said wheels by said shaft. In my present invention, the zero-setting mechanism operates on the same basic principle, but is modified to meet the different operating requirements of the present register.

Mounted upon a suitably located stud 59 (Figs. 1 and 12), on the casing 6 is a zero-setting lever 60 adapted to rock from and towards its normal idle position at its clockwise limit of travel. Fast upon one end of the number wheel shaft 21 is a toothed pinion 61 meshing with an arcuate externally toothed zero-setting segment 62 journaled upon the aforesaid stud 59 for rocking movement with the zero-setting lever 60, and having a stop arm or tail 63 normally in contact with an arresting collar 63' located on the carrying head shaft 26 to limit clockwise rotation of the segment. Advance movement of the segment 62 is arrested by contact of the internal periphery of the zero-setting segment with the collar also, as shown in Fig. 6. Fast upon the contiguous ends of the

number wheel shafts 21 and 22 are identical toothed pinions 64 and 65, respectively, (Figs. 3 and 13 to 16), relatively off-set and geared together by a suitably mounted idler pinion 66 of sufficient width to mesh with both pinions 64 and 65, whereby said number wheel shafts are rotatable through a complete cycle of movement and in the same direction by said segment 62. The number wheel shafts 21 and 22 are provided with longitudinal grooves 67 and 68, respectively, adapted upon rotation of said shafts, by advance movement of the zero-setting segment 62, to pick up pawls 69 (Fig. 18), on all number wheels 15 registering other than zero and advance the wheels in adding direction to their zero registering positions as said shafts are rotated through a complete cycle of movement clockwise. As will be clear, rotation of the number wheel shafts 21 and 22 in counter-clockwise direction by retraction of said segment 62 is idle with respect to the number wheels 15.

Since, as previously explained, the transfer devices, when tripped, lock the number wheels 15 against rotation after a transfer operation, it will be evident that an initial operation of the transfer restoring mechanism must be effected to restore to normal position any transfer devices which have been operated, as a condition precedent to a zero-setting operation. Also since the number wheels 15 trip all the transfer devices 30 during their increment of movement to their zero registering positions, it follows that a final transfer restoring operation must be effected to reset the tripped transfer devices and thus unlock said wheels after the wheels have reached their zero 35 positions. To this end, the zero-setting lever 60 is provided with a cam 70, (Figs. 1, 6 and 12) cooperating with a hooked rocker 71 pivoted at one end, at 72, to the adjacent side wall of the casing 6, the opposite free end of the rocker lying 40 in contact with a stud 52' on the carry-restoring sector 52, to operate the sector 52, and hence the transfer restoring mechanism, upon initial advance and again upon the initial retraction of the zero-setting lever 60. A pin and slot connection 73 and 74, respectively, between the zero-setting lever 60 and its segment 62 permits the lever sufficient idle or independent advance and retraction relatively to its segment, to provide for operation of the transfer restoring mechanism 50 prior to both the advance and the retraction of the segment 62.

In the invention disclosed in my co-pending application, Serial No. 505,905, heretofore mentioned, it is immaterial whether or not the cam 55 forming the toe of the zero-setting lever releases the rocker immediately after its initial operation of the transfer restoring mechanism at the outset of the counter-clockwise travel of the lever, which resets the tripped carrying devices, as the number wheels are each equipped with but a single carry-tripping tooth, and it is only necessary to insure the withdrawal of the tripped carrying devices, if any there be, prior to the advance of the number wheels in a zero-setting operation. 60

Failure to reset all tripped carrying devices prior to zero-setting operation, would enable such tripped carrying devices to maintain their wheels locked, and hence, prevent a zero-setting operation. 65

In the present invention, however, certain of the number wheels, as the farthings and the tens-of-shillings wheels, (Figs. 8 and 10), are equipped with a plurality of carry-tripping teeth 43, the farthings wheel in the illustration having three 75

equidistantly spaced carry-tripping teeth, and the tens-of-shillings wheel having five equidistantly spaced carry-tripping teeth.

It is, therefore, necessary, as heretofore stated, to modify the mechanism disclosed in application, Serial No. 505,905, in certain important particulars, to effect a rapid withdrawal of those carrying devices associated with the number wheels, as the farthings and tens-of-shillings wheels, having a plurality of carry-tripping teeth. Such withdrawal should also be effected earlier in the carry-restoring operation than the withdrawal of the carrying devices associated with those number wheels equipped with but a single carry-tripping tooth, since the zero-setting operation follows the carry-restoring operation so quickly that one of the carry-tripping teeth on the tens-of-shillings wheel, for instance, might contact the tooth 44 on its carrying head 24 before the latter is completely withdrawn from its path.

Furthermore, and fully as important, is the necessity for retaining in an over-restored position, those carrying heads associated with the number wheels equipped with a plurality of carry-tripping teeth 43, to prevent such carry-tripping teeth from tripping their carrying devices immediately after the restoration of such devices, and prior to the point in the zero-setting operation when all the carrying devices are to be tripped as the number wheels pass from their "9", or equivalent positions, to their "0" positions.

And I contrive to obtain these differences in operation with but slight mechanical changes in the structure shown in the co-pending application, Serial No. 505,905, which, nevertheless, result in considerable variation in operation.

To effect the rapid and early restoration of those tripped carrying devices which are associated with the number wheels having a plurality of carry-tripping teeth, as the farthings, and tens-of-shillings wheels, I preferably forwardly off-set the depending free ends 38' (Fig. 1) of the operating levers 32 associated with such carrying devices, so that when tripped, the free ends 38' will lie closer to the carry restoring ball 48 common to all the carrying devices, than do the free ends 38 of those carrying devices associated with number wheels equipped with but a single carry tripping tooth 43. It is obvious that, because of this arrangement, the carry-restoring ball 48, when operated by the cam 70 of the zero-setting lever, and the rocker 71, will pick up the off-set ends 38' first and start the withdrawal of their associated carrying devices before the ball 48 can operate upon the free ends 38 of the remaining carrying devices, thus imparting a lead to the carrying devices equipped with such forwardly off-set ends 38'.

As a result of off-setting the ends 38', their associated carrying devices will be withdrawn from their number wheels more suddenly and to a greater distance than are the remaining carrying devices, to accommodate which over-restoring travel of the special carrying devices, I preferably provide such carrying devices with two-part carrying heads 75, 76, (Figs. 19 to 21,) as distinguished from the single-part or integral construction of the carrying heads 24 appropriate to the remaining carrying devices.

The two-part carrying heads each includes a bearing member 75 similar to the carrying heads 24, except for the omission of the tripping tooth 44 and journaled on the pivot shafts 25, (26). A combined transfer and check dog 21, 28 is pivoted on the bearing member, the tail of which

dog is normally held against the edge of the bearing member by a spring 30 which maintains the dog at one limit of its travel. Ways 77 formed on one side face of the bearing member 75 accommodate a slotted trip member 78 adapted to slide in the ways 77, the forward end of the trip member carrying a tripping tooth 44, and the forward ends of the link 35 being pivoted to the rear end of the slotted trip member (Fig. 1).

The spring 30, the rear end of which is connected to the rear end of the slidable trip member 78 is sufficiently strong to maintain the trip member in its fully advanced position relatively to the bearing member 75, as determined by contact of the rear end of the slot 78 in the trip member against the pivot shaft 26 (25), so as to introduce the tripping tooth 44 of the slidable trip member 78 into the path of the tripping teeth 43 of the number wheel.

Obviously, the over-restoring throw imparted to the particular carrying devices, because of the off-set ends 38' of their operating levers is permitted by the slots 78 in the slidable trip members 78 to which the links 35 are pivotally connected, which permits these toggle structures, after restoration to their straightened positions, to be slid farther axially to withdraw their tripping teeth 44 completely out of the path of the number wheel teeth 43, as well as in rocking their detents 41 farther in counter-clockwise direction than the detents 41 appertinent to the one-piece carrying heads 24.

During such over-restoring throw of the carrying devices equipped with the two part carrying heads, the trip members 78 slide rearwardly relatively to the bearing members 75, and further tension the springs 30.

In case the carrying devices were in their set or cocked positions at the beginning of a zero-setting operation, the transfer restoring bar 48 would not materially affect those having the usual form of head 24, but would rock rearwardly the off-set ends 38' of the operating levers associated with the two-part heads 75, 76, and withdraw the tripping teeth 44 thereof to idle position.

As heretofore stated, however, it also is necessary to maintain the tripping teeth 44 of the slidable trip members 78 in such completely withdrawn positions until the number wheels with which the unmodified carrying devices co-act, have nearly completed their advance to their zero positions.

To effect this result, I have altered the shape of the cam 70 at the toe of the zero-setting lever 60, and have somewhat lengthened such cam, as compared with the corresponding cam shown in my copending application, Serial No. 505,905, so that the cam will maintain its control of the rocker 71 and hence, the transfer restoring mechanism, to hold the latter in effective position during almost the entire counter-clockwise or resetting throw of the zero-reset lever 60.

In the present instance, the contour of the cam 70 is so proportioned that its rear face escapes the roll 70' on the rocker 71 at just about the time that the zero-resetting segment 62 has returned the number wheels equipped with single carry-tripping teeth 43, to their "9" positions, whereupon the spring 56 (Fig. 1) quickly returns the transfer-restoring mechanism to its normal position, the rocker 71 being swung clockwise so that its roll 70' rides along the more abrupt front face of the cam 70.

Simultaneously, the operating lever springs 31 and the detent springs 42 associated with those

carrying devices having two-part heads 15, 16, advance their respective carrying devices to their normal cocked positions, during which advance, the trip members 16 slide forwardly along the ways 17 in the bearing members 15, until arrested by contact of the rear end walls of their slots 18 with the pivot shafts 25 (26).

The carrying devices of all the number wheels are now in position to be tripped by the tripping teeth 43 of their respective number wheels 15, as the wheels pass from their "9" or equivalent positions to their zero positions, it being borne in mind that the number wheels are still being advanced by the zero-setting lever 60.

15 The ensuing carrying operation of all the carrying devices to advance their respective number wheels one step, however, has no objectionable effect on the number wheels, as the latter are being advanced simultaneously by the zero-setting lever 60 through the zero-resetting segment 62, so that the number wheels arrive in their zero positions under the combined influence of their carrying devices and of the zero-setting lever, the check dogs 28 of the carrying devices at the 20 end of their carrying movements, operating to lock the number wheels against farther advance, and hence, against overthrow due to a violent operation of the zero-setting lever 60.

Returning to the start of the zero-setting operation, it will be understood that the slot 14 (Figs. 1, 6 and 12) in the zero-setting segment 30 62 is of sufficient length to enable the zero-setting lever 60 to actuate the transfer restoring mechanism and withdraw the tripped carrying 35 devices, if any, from the number wheels 15 before the stud 73 of the zero-setting lever advances the zero-setting segment from its normal idle position.

The zero-setting segment, when rocked by the 40 zero-setting lever on its counter-clockwise travel, turns the spur gear 61 and the off-set shafts 21 and 22 clockwise, the grooves 67, 68 of the shafts picking up in their advance the variously positioned number wheels 15 to turn the number 45 wheels in adding direction until their zeros appear at the sight opening 13.

As the numeral wheels 15, at this time still under the influence of the zero-setting lever, advance towards their zero positions, the tripping teeth 43 of the wheels wipe past the tripping teeth 44 of the set carrying devices and trip the latter as heretofore stated. The carrying devices operate relatively to their numeral wheels in just the same manner as when a transfer operation is 55 effected during an adding operation, but with this difference.

In an adding operation, the digits of the item being entered, are registered denomination by denomination successively, so that when the addition of a digit on the particular numeral wheel 15 at that time engaged with the master actuator 20, trips the associated carrying device, such device immediately operates on the numeral wheel of next higher order, which last named wheel 65 at that time is stationary, as are all the other numeral wheels, except the particular wheel engaged with the master actuator.

If such numeral wheel of next higher order was also turning at the time the carrying operation 70 occurred, the carry would be "lost" or swallowed.

That is precisely the condition of which I take advantage in clearing operations, since all the numeral wheels 15 are rotating forwardly under the action of the zero-setting lever 60 and its segment 62 from "9" (or its equivalent) to "0" at

the same time that all the carrying devices are tripped, and hence, although the carrying devices perform their usual carrying operations, such operations are futile and the "carries" are "lost" or "swallowed".

As a result, the numeral wheels 15 remain at their zero positions at the end of the counter-clockwise throw of the zero-setting lever 60 and segment 62, unaffected by the carrying action of the carrying devices.

10 The operator now returns the zero-setting lever 60 in clockwise direction to its normal position. Initially, the zero-resetting lever 60 moves clockwise relatively to the resetting segment 62, due to the slot and pin connections 73, 74, the abrupt 15 front face of the cam 10 at the toe of the zero-setting lever, wiping against the roll 70' on the hooked rocker 71 to shift the free end of the rocker counter-clockwise against the stud 52' on the carry-resetting sector 52 and rock the sector 20 clockwise to restore the carrying devices, all of which were tripped as the numeral wheels passed from their "9" (or equivalent) positions to their zero positions.

Continued return movement of the zero-setting 25 lever 60 causes its stud 73, after its initial idle movement, to pick up the zero-setting rack 62 and restore it to its normal raised position, the rack, in turn, reversely rotating the gear 61 and the numeral wheel shafts 21 and 22, in counter-clockwise direction to withdraw the grooves 67, 68 from the toothed ends of the pawls 69 on the respective numeral wheels, such grooves, at the end of the counter-clockwise travel of the shafts, lying just in front (to the right) of the toothed ends 30 of their pawls 69 so that subsequent in adding operations, the pawls will trail over the grooves 35 without engaging therewith.

The foregoing is a detailed description of a 40 preferred embodiment of my invention, but it is to be understood that right is herein reserved to changes and modifications falling fairly within the scope of the claims appended hereto.

What I claim is:

1. In a register, the combination with a series 45 of denominational wheels, transfer mechanism therefor, and transfer restoring mechanism, of zero-setting mechanism, and means for rendering ineffective the transfer mechanism by operation of the zero-setting mechanism and co-incidentally with operation of the transfer restoring mechanism.

2. In a register, the combination with a series 50 of denominational wheels, transfer mechanism, and transfer restoring mechanism, of zero-setting mechanism, means for rendering ineffective the transfer mechanism by operation of the transfer restoring mechanism, and means for operating the transfer restoring mechanism by initial operation of the zero-setting mechanism.

2. In a register, the combination with a series 55 of denominational wheels having multiple zero-registering positions, respectively, and transfer devices individual to the wheels and rendered operative as an incident to rotation of said wheels to zero-registering positions, of zero-setting mechanism for said wheels, and means for rendering ineffective said transfer devices by initial operation of the zero-setting mechanism.

4. In a register, the combination with a series 70 of denominational wheels having single and multiple zero-registering positions, respectively, and individual transfer devices therefor controlled by rotation of related wheels to said zero-registering positions, of zero-setting mechanism common to 75

all said wheels, and means operative by the zero-setting mechanism to render ineffective those transfer devices controlled by the wheels having multiple zero-registering positions.

5. In a register, the combination with a series of denominational wheels having single and multiple zero-registering positions, respectively, and individual transfer devices therefor controlled by rotation of related wheels to said zero-registering positions, of zero-setting mechanism common to all said wheels, and means operated by the zero-setting mechanism to restore the transfer devices, and to temporarily render ineffective the transfer devices controlled by the wheels having multiple zero-registering positions incident to the restoring operation.

6. In a register, the combination with a series of denominational wheels, of transfer mechanism, including individual transfer devices for the wheels operative to an ineffective position, zero-setting mechanism, and means to shift the transfer devices to ineffective position by operation of the zero-setting mechanism.

7. The combination with denominational wheels, and zero-setting mechanism, of transfer mechanism, including a rocking head, a motor, means for rendering the motor effective to rock the head, including a member movable into operative and inoperative relation, respectively, to one of said wheels, and means operative by the zero-setting mechanism for moving said member into inoperative relation.

8. The combination with denominational wheels, and zero-setting mechanism, of transfer mechanism, including a rocking head, a motor, means for rendering the motor effective to rock the head, including a slide on said head movable into operative and inoperative relation, respectively, to one of said wheels, and means for moving the slide into such operative and inoperative relation as an incident to operation of the zero-setting mechanism.

9. The combination with denominational wheels, and zero-setting mechanism, of transfer mechanism, including a rocking head mounted on a fixed axis, a motor, means for rendering the motor effective to rock the head, including normally aligned, pivotally connected members movable into operative and inoperative relation, respectively, to one of said wheels, and means for so moving said members as an incident to operation of the zero-setting mechanism.

10. The combination with denominational wheels, and zero-setting mechanism, of transfer mechanism, including a rocking head, a motor spring, means for rendering said spring effective to rock said head, including normally aligned, pivotally connected members urged by said spring into an operative relation to one of said wheels and movable into inoperative relation with respect thereto, and means operative by the zero-setting mechanism for moving said members into such inoperative relation.

11. The combination with denominational wheels, and zero-setting mechanism, of transfer mechanism, including a head mounted to rock on a fixed axis, a motor, and means controlled by one of the wheels, for rendering the motor effective to rock said head, including pivotally connected members having the normal relation of a toggle lock resisting said motor, one of which members is slidable on said head into operative and inoperative relation, respectively, to one of said wheels as an incident to operation of the zero-setting mechanism.

12. The combination with denominational wheels, and zero-setting mechanism, of transfer mechanism, including a head rocking on a fixed axis, a motor, means to enable the motor to rock the head under control of one of said wheels, said means including pivotally connected members having the normal relation of a toggle lock to resist the power of the motor and operative to render ineffective the transfer mechanism as an incident to restoration of the members to motor-resisting position, and means to restore the transfer mechanism by operation of the zero-setting mechanism.

13. The combination with denominational members, of transfer mechanism, including a head rocking from a normal position, a motor, means for rendering the motor effective to rock the head, and devices operative to both return the head to normal position and to render ineffective the transfer mechanism.

14. The combination with denominational members, of transfer mechanism, including a head shiftable from its normal position, a motor, and means to enable the motor to shift the head, such means including devices operative to return the head to normal position and render ineffective the transfer mechanism in succession.

15. The combination with denominational members, of transfer mechanism, including a head shiftable from its normal position, a motor, and means to enable the motor to shift the head, such means including devices having the normal relation of a toggle lock to resist the power of the motor, and operative to both return the head to normal position and to render ineffective the transfer mechanism.

16. The combination with denominational members, of transfer mechanism, including a head shiftable from its normal position, a motor, and means to enable the motor to shift the head, such means including pivotally connected members normally positioned to resist the power of the motor, and operative to both return the head to its normal position and to render ineffective the transfer mechanism.

17. The combination with denominational members, of transfer mechanism, including a head shiftable from its normal position, a motor, and means to enable the motor to shift the head, such means including devices having the normal relation of a toggle lock to resist the power of the motor, and operative to render ineffective the transfer mechanism.

18. The combination with denominational members, of transfer mechanism adapted to be tripped by one member to initiate a transfer to another, including a head rocking on a fixed axis, a motor, and operating connections between the head and motor normally resisting the urge of the latter, and including a sliding trip member on the head, and a lever operative to move the trip member to effective and ineffective positions, respectively.

19. The combination with denominational members, of transfer mechanism adapted to be tripped by one member to initiate a transfer to another, including a head rocking on a fixed axis, a motor, and operating connections between the head and motor normally resisting the urge of the latter, and including a sliding trip member on the head, and a lever operative against the urge of the motor to move the trip member to ineffective position.

20. The combination with denominational members, and zero-setting mechanism, of indi-

vidual transfer devices for said members adapted for transfer restoring, and means for restoring said devices as an incident to operation of the zero-setting mechanism, and operative to restore some of the series in advance of the others.

5 21. The combination with denominational members, and zero-setting mechanism, of individual transfer devices for said members adapted for transfer restoring, some of said transfer devices including means to render the same ineffective during transfer restoring operations, and means for restoring said transfer devices as an incident to operation of the zero-setting mechanism, and operative to restore those transfer devices which include means to render the same ineffective, in advance of the others.

10 22. The combination with value-indicating wheels, and means for driving the same, including shafts mounted in end to end staggered relation, and wheels on said shafts, of zero-setting mechanism, including a zero-setting lever, and means for rotating said shafts through one complete cycle of movement by operation of said lever.

15 23. The combination with value-indicating wheels, and means for driving the same, including shafts mounted in end to end staggered relation, and wheels on said shafts, of zero-setting mechanism, including a zero-setting lever, and means for rotating said shafts in unison

20 through one complete cycle of movement by operation of said lever.

24. The combination with value-indicating wheels, and means for driving said wheels, including shafts arranged in end to end staggered relation, and wheels on said shafts, of zero-setting mechanism, including a zero-setting lever, and means for simultaneously rotating said shafts in the same direction and through one complete cycle of movement by operation of said lever.

25 25. In a register, the combination with a series of number wheels; and tripping elements on the wheels, certain of the wheels equipped with a plurality of tripping elements; of normally cocked, transfer devices tripped by the tripping elements, those transfer devices with which a plurality of tripping elements co-act, adapted for an over-restoring travel; transfer restoring mechanism common to all the transfer devices, to reset the tripped transfer devices to cocked position, and impart a lead to those transfer devices adapted for excess restoration; and means operable upon the transfer-restoring means, and the number wheels, to first re-cock the tripped transfer devices, and then hold them re-cocked while turning the number wheels towards zero, those transfer devices to which a lead is imparted being held completely withdrawn from the number wheels which trip them.
